UNITED STATES PATENT OFFICE.

HARRY L. FERREE, OF ROCHESTER, NEW YORK, ASSIGNOR TO RICHARDSON CORPORATION, OF ROCHESTER, NEW YORK, A CORPORATION OF NEW YORK.

BEVERAGE-CARBONATING MACHINE.

Application filed July 13, 1926. Serial No. 122,117.

The invention relates to a beverage carbonating machine, more particularly of the type which receives measured quantities of syrup and water in predetermined proportions and mixes them while carbonating, the beverage then being in completed form ready to serve.

The invention is an improvement on and applicable to the general type of apparatus illustrated in Patent #1,370,213, dated March 1, 1921, and has for an object to afford a construction that insures an accurately measured and uniform quantity of syrup under all conditions, regardless of the viscosity of the syrup.

Some users of beverage carbonating machinery employ a heavier syrup than others, and it has been found that a syrup measuring device such as illustrated in the patent referred to does not give a uniform measurement for syrups of both thin and thick consistencies. The thicker the syrup, the more air it is likely to contain as it passes through the pump, and the prime desideratum of this invention is to take account of the air in the syrup and afford a pump that will always feed an exactly uniform quantity of syrup, irrespective of the amount of air it contains or the thickness of the syrup.

A further object of the invention is to afford a pump that is of simple construction, containing few parts, and which requires little attention to keep it in proper operation.

To these ends, the invention comprises the construction and arrangement of parts that will appear clearly from the following description, when read in conjunction with the accompanying drawings, the novel features being pointed out in the claims following the description.

In the drawings:

Figure 1 is a side elevation of a beverage carbonating machine equipped with a preferred embodiment of the invention, and

Figure 2 is a sectional view of the pump.

Referring more particularly to the drawings, 1 designates the usual carbonator with water feed line 2 through which water is pumped to the carbonator, and a syrup feed line 3 which enters the water line at 4 or may be otherwise connected with the carbonator. 5 is the syrup pump, while 6 is the inlet to the pump connected with any suit-

able source of syrup supply. 7 and 8 are check valves on the inlet and outlet sides of the pump 5.

The syrup pump is driven from a crank disk 10 operated from a gear 11 which engages a pinion 12, the latter being fixed on the shaft which drives the water pump, after the fashion of the patented construction already mentioned. The syrup pump comprises a cylinder 15 and plunger 16, while 17 is a connecting rod that is adjustably connected to the crank disk 10 through one of the several openings 18 which are arranged, at different distances from the center of the crank disk in order to vary the amount of travel of the plunger.

As the plunger 16 moves outwardly with reference to the cylinder 15, the check valve on the outlet side of the cylinder closes and the check valve on the inlet side opens, permitting a supply of syrup to be drawn into the cylinder. Then as the plunger travels inwardly on its operative stroke, the reverse operation of the check valves takes place and the syrup is forced from the cylinder through the syrup line and into the water line and carbonator.

In order to prevent air in the syrup from causing variations in the amount of syrup discharged, I employ an air chamber preferably arranged as shown at 20. The air chamber 20 is preferably in the form of an enlarged opening in the cylinder wall surrounding the inner end of the plunger when the latter reaches the end of its operative stroke. When in this position, the plunger extends through the enlarged portion 20 and into the plunger opening of the cylinder, so that the amount of syrup discharged is exactly that represented by the displacement of the plunger. Under normal conditions, the recess or chamber 20 will be occupied entirely or almost entirely by syrup, and a volume of syrup sufficient to fill the chamber 20 will always remain in the cylinder when the plunger reaches its innermost position.

If the syrup in the cylinder contains air, such air will be forced toward the outer portion of the pocket 20, and any variation in the air entrained in chamber 20 results merely in a variation in the amount of syrup held in the remaining portion of the chamber 20. The pocketed air cannot affect the volume of syrup dis-

charged by the operating stroke of the plunger, and such volume always remains constant because the amount of syrup forced out by the plunger will always be no more than that actually displaced by the plunger. The syrup thus displaced will always be free from air, which will take the line of least resistance and enter the outer portion of chamber 20.

10 While I have described the invention with reference to a particular embodiment, it is not confined to the precise arrangement shown, but is susceptible of various modifications and departures, either in conjunction 15 with a beverage carbonating apparatus or in other relations where it is desirable to constantly feed uniformly measured quantities of syrup, and this application is intended to cover any such arrangements as come 20 within the underlying purposes of the invention or the scope of the following claim.

I claim:

The combination with a carbonating machine adapted to receive and carbonate water and syrup, of means for accurately measuring and feeding quantities of syrup thereto, comprising a cylinder having a piston chamber, the walls of the cylinder being of reduced thickness at one end to afford a relatively small measuring chamber 30 surrounding the end of the piston when the latter is at the limit of its inward stroke, inlet and outlet pipes for the syrup communicating with said measuring chamber, syrup controlling check valves in said inlet 35 and outlet pipes, and a solid piston movable in said piston chamber and acting to feed a quantity of syrup such as is displaced by the inner end of the piston.

In witness whereof, I have hereunto signed 40 my name.

HARRY L. FERREE.
